MARIE JOSEPH CORNU, OF PARIS, FRANCE.

MERCURY-VAPOR LAMP.

1,343,037.

Specification of Letters Patent.

Patented June 8, 1920.

Application filed January 5, 1918. Serial No. 210,583.

To all whom it may concern:

Be it known that I, MARIE JOSEPH CORNU, a citizen of the French Republic, and residing in Paris, France, 26 Rue de Babylone, officer, have invented certain new and useful Improvements in and Relating to Mercury-Vapor Lamps, of which the following is a complete specification.

This invention relates to a mercury-vapor electric lamp.

The mercury arc produced in this lamp is an arc of small length but of high specific brilliancy. It is produced between the two electrodes in a thick-walled quartz tube. The thickness being generally equal to at least half the internal diameter of the tube, the heat of the arc is thereby retained, and the mercury vapor maintained at a high temperature.

There is no previously formed vacuum in the lamp. On the contrary, the internal pressure of the lamp at rest, as during normal working, is at least as great as the pressure of the atmosphere.

The cathode of the lamp is completely secured, that is to say, the mercury located therein cannot become displaced.

On the other hand the anode is free, but with strong damping, the object of which is to brake its oscillations.

In the accompanying drawing, which illustrates by way of example one constructional form of the invention:

Figure 1 is a general view of the lamp at rest,

Fig. 2 illustrates the lamp during normal working,

Figs. 3, 4, 5, and 6 are devices for striking the arc by means of heating by gas, electric filament, automatic pump or expansion bulb.

The cathode C is formed by a tube a, to which is connected the negative pole of the current supply, and which is united to a cooling chamber b.

The anode A, which is connected to the positive pole of the current generator, comprises a test-tube c united through the medium of the bent tube d to the condensing chamber e, which may or may not be provided with cooling vanes. The tube d terminates, in the middle of the test tube c, in a very narrow tube f, into which there enters a flat-headed metal pin g serving as a valve and only allowing the mercury to pass very slowly. The test-tube c is closed at

its upper end and only allows passage for the spiral-shaped current-supply terminal h pressing on the head of the pin g. The cooling chambers e and b are united to one another by the quartz tube i-j, exhibiting, in the immediate neighborhood of the cathode, a curvature k, the concavity of which is turned downward. The tube i-j has its walls of thickness equal to at least half the internal diameter of the tube.

The level of the mercury in the test tube c rises for instance as high as l-l', and, the extremity of the tube f being in the middle of the test tube, the lamp may be turned upside down with impunity into any position whatever without fear of air getting into the inside.

The object of the device adopted for the anode is to damp the oscillations of the mercury and consequently to give fixity to the arc.

I will now describe the operation of the lamp.

The lamp being filled right up and completely cleared of its gases, and current being supplied to the electrodes, all that is necessary in order to strike the arc is to produce the separation of the two meniscuses of mercury at the point k of the thick tube i-j.

The arc may be struck in several different ways:

In Fig. 3 an external source of heat such as a gas heater m is utilized, which is placed in the neighborhood of the point k. As soon as the arc is struck, that is to say, as soon as the two mercury meniscuses are separated, the source of heat is removed.

In Fig. 4 the arc is struck by means of a heating spiral of platinum or other metal n wound around the quartz tube i-j and heated by the same electric current that actuates the lamp. The spiral may be cut out of circuit either by hand or automatically as soon as the arc is struck.

In Fig. 5 a capillary tube p-p' is welded to the highest point of the thick tube i-j. By means of this tube an inert gas such as nitrogen, neon, argon, etc., or a vapor is introduced by means of a mechanical or automatic pump r. The gas or vapor under pressure pushes the meniscuses away to right and left. As soon as the arc is produced one ceases to actuate the pump r, in which the gas will resume its place, and the lamp continues to work.

2. In Fig. 6 the pump *r* is replaced by an expansion bulb *s* welded to the extremity of the capillary tube *p*—*p'* and filled with the gas that is to be introduced into the lamp. This bulb incloses a heating filament *t* connected either in series or as a shunt to the terminals of the lamp, or on an independent circuit. When the current passes through the filament *t* it becomes heated, the gas expands and pushes away the meniscuses and the arc is started. As soon as the current is cut off, the bulb *s* becomes cool again, the gas resumes its place, and the mercury arc continues to work.

15. The internal pressure of the lamp may be whatever is desired. For that purpose it suffices either to increase or to decrease the height of anode test-tube *c* and in this case the pressure is determined by the difference 20 between the level of the mercury at the point *k* and the level *l*—*l'*, or else to modify the pressure of the gas that fills the space above the mercury in the test-tube *c*. In this case the pressure is that which results from the 25 adding together pressure of the gas inside and of the height of the column of mercury. Furthermore, if the anode *A* is hermetically sealed, the pressure inside the lamp tends to increase automatically when 30 the arc becomes longer under the influence of an increase in the voltage at the terminals of the lamp.

What I claim is:

1. A mercury-vapor electric lamp, comprising a mercury tube having cooling chambers and a thick walled-bent quartz portion connecting the chambers, the cathode end of the tube being closed and the anode end provided with means for damping the oscillations of the mercury, and means for varying the pressure in the tube.
2. A mercury vapor electric lamp, comprising a mercury tube having cooling chambers and a thick walled bent portion 45 connecting the chambers, the cathode end of the tube being closed and the other end

open, a chamber forming the anode and into which the open end of the tube extends, a valve for the open end of the said tube, a conductor, and a spiral carried by 50 the conductor and engaging and pressing said valve.

3. A mercury vapor electric lamp, comprising a tube containing mercury and having cooling chambers and a bent portion 55 having a contracted passage and connecting the said chambers, the cathode end of the tube being closed and the other end reduced and open, a chamber forming the anode and into which extends the open and reduced 60 end of the tube, a valve for the said open end of the tube, a conductor, a spiral spring carried by the conductor and engaging and pressing on the valve, and means for forcing the mercury out of the said contracted 65 passage.

4. In a mercury vapor electric lamp, a mercury tube having an intermediate bent quartz portion, and means for striking the arc, comprising a capillary tube secured to the 70 quartz tube, an inert gas or vapor chamber with which the capillary tube is connected, and means for forcing the gas or vapor from the chamber into the bent portion of the mercury tube to expand the same to cause 75 the striking of the arc independently of the vaporization of the mercury.

5. In a mercury vapor electric lamp, a mercury tube having an intermediate bent and reduced portion, and means for striking the arc, comprising a capillary tube secured to the reduced portion of the mercury tube, an expansion gas bulb with which the capillary tube is connected containing an inert gas, and a heating filament in the bulb 85 for expanding said gas to strike the arc.

In testimony whereof I have hereunto set my hand at Paris (France), this 5th day of February, 1918.

MARIE JOSEPH CORNU.

In the presence of—

CHAS. P. PRESSLY.
